UNITED STATES PATENT OFFICE.

JOHN B. RAUEN, OF LOS ANGELES, CALIFORNIA, ASSIGNOR TO UNITED STATES BUMPER COMPANY, INC., OF LOS ANGELES, CALIFORNIA, A CORPORATION OF CALIFORNIA.

BUMPER.

Application filed May 20, 1925. Serial No. 31,612.

To all whom it may concern:

Be it known that I, JOHN B. RAUEN, a citizen of the United States, residing at Los Angeles, in the county of Los Angeles and State of California, have invented a new and useful Bumper, of which the following is a specification.

This invention relates to bumpers, and more particularly to an improved form of construction of a bumper having a plurality of spaced spring steel forward impact bars and which is supported in the center in such a manner as to provide a resilient impact section between its ends of approximately uniform resistant characteristics as the same is distorted from its proper position by the impact force.

Spring steel bumpers, as now constructed, are for the most part either unsupported at the central point or are of such construction that the same prevents any yielding of the bumper at such a single point much in the manner as if a post was mounted upon the frame in the center thereof.

These latter bumpers are of such construction that if the bumper is subjected to an impact force at its center the frames of the motor vehicle will be the part thereof that is damaged. The former class of bumpers are of such construction that if the bumper receives an impact in its center portion it will offer practically no resistance or protection to the center part of the motor vehicle, such as the radiator and the like.

An object of this invention is to provide a bumper having a supported central section that will offer a substantial resistance to impact at this point but which is not so resistive as to prevent the bumper from yielding at this point so that the frame of the motor vehicle will not be damaged.

Other objects and advantages of this invention will be apparent from the following detailed description thereof as illustrated in the accompanying drawings.

In the drawings:

Fig. 1 is a front elevation of a bumper embodying this invention.

Fig. 2 is a top plan view of the bumper illustrated in Fig. 1.

Fig. 3 is a top plan view of a modified form of bumper embodying this invention.

Fig. 4 is a top plan view of a third form of bumper embodying this invention.

Fig. 5 is a sectional end elevation, taken substantially on the line 5—5 of Fig. 1.

Fig. 6 is a sectional rear elevation taken substantially on the line 6—6 of Fig. 2.

In the preferred embodiment of this invention, 1 illustrates a forward impact section preferably composed of spaced spring steel bars 2 and 3, looped at their ends as illustrated at 4 and provided at their end-most portion with eyes 5. A pair of spring steel bars 6, 7 are secured to the frame members 8 of the motor vehicle by any suitable means, such as illustrated at 9. The two spring bars 6 and 7 are provided at their extremities with eyes 10, 11, the eyes 10 being fitted between the eyes 5 of the bars 2 and 3 and a pin 12 being passed therethrough. The bars 6 and 7 are of a less bend or bow in their free position as is illustrated by the dotted lines in Fig. 2 than when the same are sprung into position to be engaged in the bracket 13 by means of the pins 14 which pass through the eyes 11 thereof.

This springing of the bars 6 and 7 into position enables the same to present a greater resistance to an impact force at the central portion of the bumper. The bracket 13 is formed in two parts, a rearward casting 15 which provides ears 16 through which the pins 14 are passed, and a forward section 17 which provides the monogram casting for the bumper. The casting 15 is provided with an extended section 18 which projects between the bars 2 and 3 of the bumper and provides shoulders 19 to hold the same spaced apart. A bolt 20 is passed through the two castings and maintains the same in position.

The modified form of this invention illustrated in Fig. 3 differs from the modification thereof illustrated in Figs. 1 and 2 in that the ends of the bars 2 and 3 are not bowed, as at 4 in Figs. 1 and 2, but are slightly curved rearwardly as illustrated at 4' and in that the bars 6' and 7' are supported at their inner ends on pins 14' which are adapted to ride in slots 21' formed in the rearward casting 15'. This construction and manner of assembling enables the bars 6 and 7 to be extended at their inner ends when the bumper is subjected to a slight impact, and the bars 6' and 7' being bowed in a reverse manner to the bars 6 and 7, the ends thereof

will retain the pins 14' at the outer points of the slots 21'. The bars 6' and 7' are of a greater bend or bow in their free position as is illustrated in dotted lines in Figure 3 so that when the same are sprung into position to be engaged with the slots 21', the same will be maintained in the outer extensions of the slots 21' and so that the initial resilient effect of the bumper will be obtained through the distortion of the bars 6' and 7'.

The modification of this invention illustrated in Fig. 4 differs only from the modification thereof illustrated in Fig. 3, in that shackles 22'' are provided for supporting the bars 6'' and 7'' at their inner ends instead of the slots 21' and in that the ends of the bars forming the impact section 1 are not looped or curved rearwardly, but extend straight out transversely of the motor vehicle and provide eyes 4'' at their ends. The bars 6'' and 7'' are bowed in the same manner as the bars 6' and 7' as illustrated in dotted lines in Figure 4.

Having fully described a preferred embodiment of this invention, and several modifications thereof, it is to be understood that I do not wish to be limited to the exact construction herein set forth, or the modifications thereof, which may, obviously, be varied in detail without departing from the spirit of the invention as set forth in the appended claims.

I claim:

1. In a bumper, a forward impact section comprising a plurality of spaced bars, and a rear supporting section including a pair of separate bars connected at their outer ends to the forward impact section, and connected at their inner ends in strained condition to the forward impact section intermediate the ends thereof.

2. In a bumper, a forward impact section comprising a plurality of spaced bars, and a rear supporting section including a pair of separate bars connected at their outer ends to the impact section, and connected in strained condition at their inner ends to a casting, said casting being adapted to maintain the said bars spaced intermediate its ends.

3. In a bumper, a forward impact section comprising a plurality of spaced bars, and a rear supporting section including a pair of curved spring steel bars and means for securing the ends of the spring steel bars to the forward impact section in strained condition. 55

4. In a bumper, a forward impact section comprising a plurality of spaced bars, and a rear supporting section including a pair of separate bars connected at their outer ends to the forward impact section and connected at their inner ends to the forward impact section intermediate the ends thereof, in 60 strained condition. 65

5. In a bumper, a forward impact section comprising a plurality of spaced bars, and a rear supporting section including a pair of separate bars connected at their outer ends to the impact section and at their inner ends to a casting in strained condition, said casting being adapted to maintain the said bars spaced intermediate its ends said supporting bars being maintained in position 70 against their normal tendency to bend. 75

6. In a bumper, a forward impact section comprising a plurality of spaced bars, and a rear supporting section including a pair of separate bars connected at their inner ends to a casting in strained condition, said casting being adapted to maintain the said bars spaced intermediate its ends, said supporting bars being secured to the said casting in a manner to permit relative movement of their inner ends. 80 85

7. In a bumper, a forward impact section comprising a plurality of spaced bars, and a rear supporting section including a pair of bowed separate bars connected at their outer ends to the impact section and at their inner ends to a casting, said casting being adapted to maintain the said bars spaced intermediate its ends said supporting bars being maintained in position 90 against their normal tendency to bow, said supporting bars being secured to the said casting in a manner to permit relative movement of their inner ends. 95

Signed at Los Angeles, California, this 11th day of May 1925.

JOHN B. RAUEN.
